UNITED STATES PATENT OFFICE

2,487,157

SANDER

Fred J. Mason, Syracuse, N. Y.

Application May 27, 1946, Serial No. 672,613

9 Claims. (Cl. 291—19)

1

This invention relates to a sander, and more particularly to a sand distributor for vehicles.

An object of the invention is to improve the traction of the wheels of a vehicle on icy or slippery roads.

Another object is to preserve the device in readiness for instantaneous operation during periods of sub-freezing weather as well as periods of warmer weather.

A further object is to deposit sand or like granular material on a roadway immediately in advance of the traction or braking wheels of a vehicle.

The above and other objects may be attained by employing this invention which embodies among its features a sand reservoir carried by the vehicle, a sand discharge nozzle carried by the vehicle in advance of selected ground contacting wheels, a conveyor tube for delivering sand from the reservoir to each discharge nozzle, and means in each conveyor tube extending into the reservoir for agitating the sand in the reservoir and effecting positive delivery of the sand from the reservoir to the discharge nozzles.

Other features include heating means for each discharge nozzle and means operable in unison with the opening of the sand discharge valves for setting the agitators in motion to deliver sand to the discharge nozzles.

In the drawings,

Figure 1 is a side view of a passenger vehicle equipped with my improved sander, certain portions of the vehicle being broken away to more clearly illustrate certain details of construction,

Figure 2 is a transverse sectional view through Figure 1,

Figure 3 is a fragmentary enlarged sectional view through the sand reservoir and sand conveyor tube, showing its relationship with one example of a delivery nozzle,

Figure 4 is a sectional view taken substantially along the line 4—4 of Figure 3,

Figure 5 is a fragmentary sectional view of a delivery nozzle of modified form,

Figure 6 is a fragmentary view partially in section of the hot gas distributing system by which the nozzle illustrated in Figure 5 is supplied with heating fluid,

Figure 7 is a transverse sectional view taken substantially along the line 7—7 of Figure 6,

Figure 8 is a diagrammatic view of the method of supplying products of combustion from an internal combustion engine to the heater illustrated in Figure 5,

Figure 9 is a fragmentary sectional view illustrating an electrically heated nozzle,

Figure 10 is a diagrammatic view illustrating the application of my device to a vehicle equipped with a conventional air pressure supply system, and

2

Figure 11 is an enlarged side view of my control valve equipped with a control switch arranged for coincidental operation with the valve.

Referring to the drawings in detail, a road vehicle designated generally 15 which in the present illustration takes the form of a passenger bus is equipped with a conventional body 16 supported on front steering wheels 17 and rear traction wheels 18. The vehicle 15 is equipped with the conventional steering wheel 19 carrying my control valve 20 and a power source in the preferred embodiment takes the form of a conventional water cooled internal combustion engine.

My improved sanding device is designated generally 22 and in its preferred form comprises a reservoir 23 having an inclined bottom wall 24 provided near one end with a discharge passage to which a conveyor tube 25 is connected so that the contents of the reservoir may be discharged therefrom with the aid of gravity. The reservoir 23 is preferably situated within the body 16 of the bus at any convenient point as for instance, under a seat as suggested in Figures 1 and 2, and its top side is closed by a suitable removable cover 26 by means of which sand may be introduced into the reservoir. In its preferred form, there are two reservoirs 23, one on each side of the vehicle in advance of the traction wheels 18 and the conveyor tubes lead downwardly therefrom to my improved sand distributing nozzle designated generally 27.

Each sand distributing nozzle comprises a tubular body 28 having a port 29 in its side which communicates with its respective conveyor tube 25, and slidably mounted within the housing 30 adjacent the port 29 is a vertically movable door 31 of arcuate configuration which when moved to its lowermost position closes the port 29 to prevent the discharge of sand from the conveyor tube 25 into the nozzle. Built into the upper end of the cylindrical body 28 is an air cylinder 32 in which a piston 33 is operable. This piston is provided with a piston rod 34 which projects through a suitable packed opening 35 in the bottom wall of the cylinder 32 and is connected to an arm 36 carried at the lower end of the door 31, so that as the piston 33 moves within the cylinder 32 the door 31 may be moved to open or closed position. The upper and lower ends of the cylinder 32 are provided with ports 37 and 38 respectively which are connected to any suitable source of air pressure supply carried by the vehicle through a control valve to be more fully hereinafter described.

Secured to the lower end of the cylindrical body 28 and communicating with the interior thereof are sand distributing nozzles 39 through which the sand flowing downwardly from the reservoir 23 is distributed adjacent its respective traction wheel. As illustrated in Figures 2 and

4 there are two nozzles 39 to each discharge nozzle 28 in order to deposit the sand in front of the traction wheels of a vehicle equipped with dual tires. It is to be understood however, that where only a single tire is mounted on each wheel, only one nozzle 39 need be employed. The nozzles 39 are surrounded by a suitable water jacket 40 provided with inlet and outlet ports 41 and 42 respectively which are connected through the medium of insulating pipes 43 and 44 respectively, with the cooling system of the engine 21. A suitable pump 45 may be interposed in the return line 44 in order to aid in the circulation of heated cooling fluid through the water jacket 40.

In order to maintain the sand contained within the reservoir 23 in a loose and flowable condition, and also positively to deliver the sand from the reservoir to the nozzle 27 I provide a conveyor screw 46, one end of which is journalled in a suitable bearing 47 carried within the reservoir 23, while the opposite end is journalled in a suitable bearing 48 carried near the extreme lower end of the tube 25. A bevel pinion 49 is mounted in driving relation axially of the conveyor screw 46 and meshes with a bevel drive pinion 50 carried adjacent one end of a stub shaft 51 which is mounted to rotate about a horizontal axis through the conveyor tube 25 adjacent its lower end. Mounted in any suitable position on the underside of the vehicle body 16 between opposite discharge nozzles 27 is an electric drive motor 53, opposite ends of the drive shaft of which are connected by means of flexible shafts 54 with the stub shafts 51, so that when the motor 53 is driven, the spiral conveyors 46 will be driven in unison. It will thus be seen that the portion of the spiral conveyor 46 which extends into the reservoir 23 will serve as an agitator to maintain the sand contained therein in a loose and flowable condition, while that portion of the agitator or conveyor 46 extending through the conveyor tube 25 will serve to feed the sand from the reservoir 23 into the discharge nozzle 27.

In the modification illustrated in Figures 5, 6, 7 and 8, each distributing nozzle 39 instead of being surrounded by a water jacket 40 is enclosed in a circumferential casing 55 having a port 56 which is connected by means of a suitable tubular connection 57 with a hollow cylindrical casing 58. The casing 58 is provided with an end inlet which is connected through the medium of a pipe 59 with the muffler 60 (Fig. 8) through which the products of combustion emitted by the engine 21 are normally discharged. Instead of being discharged directly to atmosphere as in the ordinary manner, the products of combustion are directed into the chamber 58 and thence through valve ports 61 into the pipes 57 from whence they are directed through the jackets 55 to atmosphere around the nozzles 39. The valve ports 61 are equipped with butterfly valves 62 which operate in unison by means of a common shaft to which a lever 63 is fixed. This lever is connected by a suitable flexible cable 64 to any suitable control device located in the vicinity of the steering wheel 19 so as to be readily controlled by the driver of the vehicle. Mounted on the end of the shaft opposite the lever 63 is a lever arm 65 to which a retractile coil spring is connected, the opposite end of which is connected to a fixed bracket 66 so that the butterfly valves 62 are normally held in a closed position. In order to provide for the escape of the prod-

ucts of combustion from the interior of the chamber 58 I provide an enlarged port 67 adjacent the ports 61, and connected to the port 67 is an exhaust discharge pipe 68.

5 As a further modification of the heating means for the nozzles 39 I find it in some instances, desirable to surround the nozzles with electric heating coils 69 which are housed within a casing 70 enclosing the nozzles, and connected as by leads 71 to any suitable source of electrical power supply.

15 In order to control the operation of the motor in unison with the opening and closing of the gates 31, I employ an improved control valve and switch designated generally 72 (Fig. 11). This valve is provided with a port which is connected through the medium of a pipe 73 to any suitable source of fluid pressure supply, such as the fluid pressure reservoir of a conventional air 20 brake system employed on motor vehicles. The valve 72 is also equipped with ports 74 and 75 which are connected through the medium of pipes 76 and 77 respectively, to the ports 37 and 38 of the cylinders 32. Operating in unison with 25 the valve 72 is an electrical switch 78, one terminal of which is connected to a suitable source of electrical power 79 while the opposite terminal is connected through a lead 80 with one terminal of the motor 53. The opposite terminal of the 30 power source is connected through a lead 81 to the opposite terminal of the motor 53 and it will thus be seen that when the valve 72 is manipulated so that air is admitted to the cylinders 32 to elevate the pistons 33 and open the doors 31, the motor 53 will be energized to drive the spiral 35 conveyors 46. Connected in the circuit, and operable by the manipulation of the switch 78 is a signal lamp 82 which is energized when the motor 53 is energized in order to give a visual 40 signal to the operator of the vehicle that the sanding equipment is in operation.

Obviously as the doors 31 are elevated, and the 45 motor 53 is set into operation, sand will be delivered from the reservoir 23 through the conveyor tube 25 and into the discharge nozzle 27 to be distributed through the distributing nozzles 39 immediately in front of the traction wheels of the vehicle upon which the device is used. In this 50 way, the vehicle operator may have under his direct control a means for improving the traction of the vehicle either when applying the brake, or when applying power. It is evident that such a device will not only materially aid in maintaining transportation schedules, but will also avoid 55 skidding of the vehicle with the consequent danger of accident.

While in the foregoing there has been shown and described the preferred embodiment of this invention it is to be understood that minor 60 changes in the details of construction, combination and arrangement of parts may be resorted to without departing from the spirit and scope of the invention as claimed.

I claim as my invention:

65 1. A sander for a trackless vehicle which includes, a sand reservoir carried by the vehicle, a sand discharge nozzle carried by the vehicle in advance of selected ground contacting wheels, a conveyor tube for delivering sand from the reservoir to each discharge nozzle, means extending through each conveyor tube and into the reservoir for agitating the sand in the reservoir and effecting positive delivery of the sand from the reservoir to the discharge nozzles, a closure plate 70 between said conveyor tube and discharge nozzle,

and fluid pressure actuated means connected to a source of fluid pressure carried by said vehicle to operate said closure plate and control the delivery of sand.

2. A sander for a trackless vehicle which includes, a sand reservoir carried by the vehicle, a sand discharge nozzle carried by the vehicle in advance of selected ground contacting wheels, an upwardly inclined sand conveyor tube extending between the reservoir and the discharge nozzle, means extending through each conveyor tube and into the reservoir for agitating the sand in the reservoir and effecting positive delivery of the sand from the reservoir to the discharge nozzles, a closure plate between said conveyor tube and discharge nozzle, and fluid pressure actuated means connected to a source of fluid pressure carried by said vehicle to operate said closure plate and control the delivery of sand, and heating means for each discharge nozzle below the level of the reservoir whereby heat generated by the heating means will be conducted through the conveyor tube to the reservoir.

3. A sander for a trackless vehicle which includes, a sand reservoir carried by the vehicle, a sand discharge nozzle carried by the vehicle in advance of selected ground contacting wheels, an upwardly inclined sand conveyor tube extending from the reservoir to discharge nozzle, and means extending through each conveyor tube and into the reservoir for agitating the sand in the reservoir and effecting positive delivery of the sand from the reservoir to the discharge nozzle, a closure plate between said conveyor tube and discharge nozzle, and fluid pressure actuated means connected to a source of fluid pressure carried by said vehicle to operate said closure plate and control the delivery of sand, and means surrounding each discharge nozzle to preserve the fluidity of any moisture in the discharge nozzle and in the conveyor tube.

4. A sander for a trackless internal combustion engine driven vehicle which includes a sand reservoir carried by the vehicle, a sand discharge nozzle carried by the vehicle in advance of each traction wheel thereof, a conveyor tube extending between the reservoir and the sand discharge nozzles, and a conveyor screw extending through each conveyor tube and into the reservoir for agitating the sand in the reservoir and effecting positive delivery of sand from the reservoir to the discharge nozzles, a closure plate between said conveyor tube and discharge nozzle, and fluid pressure actuated means connected to a source of fluid pressure carried by said vehicle to operate said closure plate and control the delivery of sand, a heating jacket surrounding each discharge nozzle and means for directing a heating fluid from the engine through each jacket to preserve the fluidity of any moisture in the nozzles.

5. A sander for a trackless vehicle which includes, a sand reservoir carried by the vehicle, a sand discharge nozzle carried by the vehicle in advance of selected ground contacting wheels, a conveyor tube for delivering sand from the reservoir to each discharge nozzle, means extending through each conveyor tube and into the reservoir for agitating the sand in the reservoir and effecting positive delivery of the sand from the reservoir to the discharge nozzles, a closure plate between said conveyor tube and discharge nozzle, and fluid pressure actuated means connected to a

source of fluid pressure carried by said vehicle to operate said closure plate and control the delivery of sand, and common drive means for the sand agitating means.

5 6. A sander for a trackless vehicle which includes, a sand reservoir carried by the vehicle, a sand discharge nozzle carried by the vehicle in advance of selected ground contacting wheels, a conveyor tube for delivering sand from the reservoir to each discharge nozzle, means extending through each conveyor tube and into the reservoir for agitating the sand in the reservoir and effecting positive delivery of the sand from the reservoir to the discharge nozzles, a closure plate between said conveyor tube and discharge nozzle, and fluid pressure actuated means connected to a source of fluid pressure carried by said vehicle to operate said closure plate and control the delivery of sand, heating means for each discharge nozzle, and common drive means for the sand agitating means.

10 7. A sander for a trackless vehicle which includes, a sand reservoir carried by the vehicle, a sand discharge nozzle carried by the vehicle in advance of selected ground contacting wheels, a conveyor tube for delivering sand from the reservoir to each discharge nozzle, agitating means extending through each conveyor tube and into the reservoir for agitating the sand in the reservoir and effecting positive delivery of the sand from the reservoir to the discharge nozzles, a closure plate between said conveyor tube and discharge nozzle, and fluid pressure actuated means connected to a source of fluid pressure carried by said vehicle to operate said closure plate and control the delivery of sand, and valves operable in unison with the starting of the agitating means to permit the delivery of sand to the discharge nozzles.

15 8. The combination of claim 1, wherein simultaneous actuation of said fluid pressure means and said agitating means is controlled by an electric switch on said vehicle.

20 9. The combination of claim 1, wherein said plate includes an arm and a piston in said fluid pressure means connected to said arm to move said plate when said piston is actuated.
